J. B. LASKOWITZ.

AUTOMATIC SAFETY GAS SHUT-OFF.
APPLICATION FILED MAY 20, 1921.

1,418,082.

Patented May 30, 1922.

Isidor B. Laskowitz Inventor

By his Attorney
George C. Heinricke

UNITED STATES PATENT OFFICE.

ISIDOR B. LASKOWITZ, OF NEW YORK, N. Y.

AUTOMATIC SAFETY GAS SHUT-OFF.

1,418,082.

Specification of Letters Patent. Patented May 30, 1922.

Application filed May 20, 1921. Serial No. 471,214.

To all whom it may concern:

Be it known that I, ISIDOR B. LASKOWITZ, a citizen of the United States, residing at New York, county of New York, and State 5 of New York, have invented certain new and useful Improvements in Automatic Safety Gas Shut-Offs, of which the following is a specification.

This invention relates to improvements 10 in devices for automatically cutting off the supply of gas to a gas burner, particularly to improvements in devices of this kind with which a thermostatic controlling mechanism is used.

15 It is the principal object of this invention to improve the existing devices of this kind to provide a device which is of simple construction and therefore inexpensive to manufacture which however can be readily applied to any burner and which will positively act if required.

Another object of the invention is the provision of a device of this type which employs a spring to hold the cock closed and 25 which is under the control of a thermostatic mechanism influenced by the heat of the flame, when the device is set to hold the cock open, while it will be automatically closed upon the contraction of the thermostatic mechanism when the flow of gas is 30 interrupted or the flame is extinguished in any manner other than by closing the burner or gas supply valve, by a draft of air, etc.

A still further object of the invention is 35 the provision of a device of this type which is also well adapted for use with burners using gas mantles.

These and other objects will become more 40 fully apparent as the description of the device proceeds, reference being had to the accompanying drawing forming a material part of my invention, and in which:

Figure 1 is a front elevation of a gas burner equipped with a device constructed 45 according to the present invention.

Figure 2 is an end elevation thereof.

Figure 3 shows in fragmentary detail view the thermostatic operating mechanism.

Figure 4 is a view, similar to Figure 1 of 50 a modified form of my invention, and

Figure 5 is a detail view illustrating a gas mantle adapted for use with my invention.

Referring to the drawing, the burner 10 55 of a gas fixture of the conventional type is attached to a pipe-line 11 leading thereto

from any desired source of supply and in this pipe line a gas cock 12 is arranged having a rotary valve plug therein for the control of the gas supply to the burner 10. 60

The stem 13 of the plug is extended through the casing of the cock and carries at one end a head 14 through which an operating rod 15 is passed, while its opposite end also projecting from the casing carries 65 a stop collar 16 secured on the stem by means of a screw 17 or the like and provided at its lower end with two spaced projections or noses 18 adapted to engage a stop pin 19 centrally secured between both noses 70 18 in the cock casing for limiting the valve motion in either direction.

Intermediate its ends the rod 15 has secured thereto one end of a spring 20, the other end of which is secured by a screw 21 75 or the like to a U-shaped frame 22 consisting of two parallel spaced, angular members held together by set screws 23 and 24 between which the burner 10 passes, which carries at its upper end the usual top 25 80 from which the flame 26 issues.

The spring 20 normally holds the valve with the cock in its closed position, and the rod 15 has secured to its rear end 27 an angular arm 28 carrying a horizontally disposed roller 29 at its upper free end. 85

A pin 30 is secured between the upper ends of the angular member of the frame 22, and the hook-shaped end 32 of a thermostatic rod 34 is engaging the pin 30, while 90 the opposite, also hook shaped end 33 of this rod 34 is engaging a pin 31 of a rocker arm 35, pivotally secured near its upper end, as at 36 between the two members of the frame 22. 95

To the free front end of the operating rod 15 is attached a depending chain 37 ending in a ball 38 for the purpose of operating rod 15 when it is desired to set the rod for retaining the valve of cock 12 in its open 100 position with the horizontal roller 29 engaging the lower side face of the rocker arm 35.

In the modification of my device illustrated in Figure 4 the U-shaped frame consisting of the two parallel spaced members 105 is replaced by a solid casting 39 through a collar 40 of which the burner 41 is passed and held therein by a set screw 42.

The thermostatic rod 43 in this form has screw threaded ends 44 provided with right 110 and left hand thread 45, one of which is screwed into the upper end of the casting

while the other is screwed into an operating arm 46 pivotally secured as at 47 to the upper end of the opposite end of the casting.

The device is otherwise constructed as described above with respect to the preferred form illustrated in Figure 1.

Figure 5 illustrates the application of the device to a burner 48 with which a mantle 50 of the customary construction is used. As shown, the customary metal base 51 of the mantle, which is suspended from a rod 52 in the well known manner, has a longitudinal slot 53 in which is guided the thermostatic rod 54.

15 The device operates as follows—

By a pull on chain 37 the valve of cock 12 is opened against the action of the spring 20 and the roller 29 is engaged with the side face of the rocker arm 35 which is swung out laterally from the frame 22 in the manner illustrated in Figure 1 in order to hold the valve of the cock in its open position to supply gas to the burner 10 which has been ignited previously while the chain is held in order to heat the thermostatic rod 34 so that it expands and allows a swinging out of the arm 35.

When now for one reason or the other, the flame is extinguished without the gas flow being interrupted in the customary manner, by the closure of the gas supply cock, the thermostatic rod will cool off and contract so that the arm 35 is swung inwardly around its pivot 36 and the roller 29 is disengaged from the arm and allows the spring 20 to close the valve of cock 12.

The modified device illustrated in Figure 4 operates in a similar manner, only the right and left hand thread at the ends of the thermostatic rod 43 minimizing the lost motion due to the play of pins 30 and 31 of the device illustrated in Figure 1 and further to assist the expansion and contraction of the rod 43, and consequently to make the disengagement between roller 29 and arm 46 more positive. The casting 39 and tip holder 40 may also suitably be made in one piece to prevent any possibility of the device working itself loose.

50 The above disclosure is to be regarded as descriptive only and not as restrictive or limitative of the invention, of which obviously an embodiment may be constructed including many minor modifications without departing from the general scope herein indicated and hereinafter claimed.

I am aware that various devices for similar purposes have been the subject of prior invention and I do not desire the present invention to be confounded therewith, but what

I do claim as new and desire to secure by Letters Patent of the United States is:

1. In a device of the character described including a thermostatic rod, in combination with a gas fixture and a valved burner, a mantle having its lower metal socket longitudinally slotted for the reception of said thermostatic rod, substantially as described and for the purpose set forth.

2. In a device of the character described, in combination with a gas fixture and a valved burner, an operating rod secured to the stem of said burner valve and having a bent rear end, means for manually operating said rod, a frame, a spring secured to said rod and said frame for normally holding said valve closed, a rocker arm pivotally secured at its upper end to said frame, a thermostatic rod held by said frame and a roller at the upper bent rear end of said rod adapted to engage the rear face of said rocker arm to hold the valve open when said thermostatic rod is heated, and to be disengaged from said rocker arm when said thermostatic rod is cooled off upon the extinguishing of the burner flame, to move said rocker arm against said frame, and allowing a closure of said burner valve by its spring and a mantle having a slotted socket for the reception of said thermostatic rod.

3. In a device of the character described, in combination with a gas fixture and a valved burner of a frame, a casting secured to said burner, a thermostatic rod in said frame having screw threaded ends with right and left hand screw thread, a means for normally holding said burner valve closed, an operating rod for said valve, a rocker arm pivoted to said casting at its upper end, adapted to be engaged by said thermostatic rod below its pivot point, an angular end on said valve operating rod, a horizontal roller at the upper end of said rod adapted to engage the lower side face of said rocker arm when said thermostatic rod is heated for keeping the supply valve for said burner valve open, said roller adapted to be disengaged from said rocker arm when said thermostatic rod is cooled off and contracted after the flame of the burner is extinguished, said disengagement operating means for normally holding the burner valve closed to shut off the supply of gas to said burner and an incandescent mantle having its metal socket slotted for the reception of said thermostatic rod.

In testimony whereof I have affixed my signature.

ISIDOR B. LASKOWITZ.
